INVENTOR:

George B. Chadwick,

By E. D. Chadwick,
Attorney.

UNITED STATES PATENT OFFICE.

GEORGE B. CHADWICK, OF PORTSMOUTH, NEW HAMPSHIRE.

ADJUSTABLE REAMER.

1,210,904.

Specification of Letters Patent. Patented Jan. 2, 1917.

Application filed March 14, 1916. Serial No. 84,060.

To all whom it may concern:

Be it known that I, GEORGE B. CHADWICK, a citizen of the United States, residing at Portsmouth, in the county of Rockingham 5 and State of New Hampshire, have invented certain new and useful Improvements in Adjustable Reamers, of which the following is a specification.

This invention relates to reamers, taps and 10 similar tools in which the blades are capable of radial adjustment, and is intended to provide a simple and effective arrangement for progressively adjusting the blades in such a tool.

15 My invention is herein illustrated and described as embodied in a cylindrical reamer in which the blades are driven at their front ends, as set forth in my co-pending application Serial No. 80,292, filed February 24, 20 1916, and resides in certain features of construction and arrangement hereinafter explained in connection with the accompanying drawing, in which:

Figure 1 is a side elevation of the reamer, 25 as preferably constructed; Fig. 2 is mainly a central longitudinal section through the same; Fig. 3 is a transverse section on the line 3—3 in Fig. 2; Fig. 4 shows the front end of the driving mandrel in rear elevation; and Fig. 5 is a sectional view similar to Fig. 2, but showing the parts in a different position of adjustment.

The reamer illustrated in the drawing 35 comprises a driving mandrel 2 having at its front end a cylindrical enlargement 3 which constitutes a unitary part of the mandrel and is provided with a number of notches 4, each of which extends radially inward from the periphery of the enlargement and also 40 longitudinally through the latter. These notches 4 correspond in number with the detachable blades 5 employed in the reamer, eight of them being shown, although the precise number is immaterial. The enlargement 45 3 is also provided on its rear face with a like number of rearwardly-extending projections 6, each of which is located at the bottom of one of the notches 4 and has its rear face 7 slanted inward and forward, its 50 outer face being preferably flush with the

bottom of the corresponding notch. On the mandrel 2 is mounted a cylindrical shell 8 provided externally with longitudinally-extending grooves 9 which correspond in number, width and position with the notches 4 55 but at their front end are enough deeper than said notches to receive the projections 6, so that the front end of the shell is adapted to abut against the rear face of the enlargement 3. A nut 10 mounted on a threaded portion 11 of the mandrel 2 behind the shell 8 serves to clamp said shell in any given position of adjustment, as hereinafter described.

In each of the grooves 9 and the corresponding notch 4 is located one of the blades 5, the inner portion of which is cut away at its front end to provide an angular recess 12 adapted to receive the corresponding projection 6, as shown in Figs. 2 and 5, the inner 70 edge of the blade being supported by the shell 8. In the specific reamer illustrated each blade 5 has a longitudinal cutting edge 13 extending parallel with the axis of the reamer and a transverse cutting edge 14 at 75 the front end of the blade, so that the tool is adapted to ream a cylindrical bore having a closed bottom and to face the bottom of the bore at its periphery, but so far as my present invention is concerned it is immaterial whether the blades are shaped to provide a cylindrical tool or a tapering tool, 80 or whether they have cutting edges at their front ends or not. All of the blades employed, which are exactly alike, are simultaneously clamped in place by means of a concave nut 15 mounted on an externally-threaded portion of the shell 8 and engaging the slanting rear ends of the several blades in the usual way, the clamping nut 15 90 being preferably backed up by a lock nut 16.

As described thus far the construction is practically the same as that shown and described in my co-pending application above referred to and has the same advantage, 95 namely, that when the reamer is in use the driving power applied to the mandrel is carried forward and transmitted to the blades at their front ends where the heaviest duty is imposed upon them, so that the rear por- 100

tions of the blades are practically free from twisting strains and hence are not liable to be broken or distorted sufficiently to prevent the reaming operation from forming a true surface. In my prior construction, however, the blades are adjusted outward by placing shims beneath them, whereas in the present case I am enabled to dispense with the shims by forming the bottom of each 5 groove 9 at an angle with respect to the axis of the reamer and causing the blades to rest directly on the shell 8 in all positions of adjustment. As shown in Figs. 2 and 5, the bottom of each groove 9 is slanted in such 10 manner that its front end is nearer the axis of the reamer than its rear end, the inner edges of the blades 5 being formed on a corresponding slant, and as a result of this construction the blades can be adjusted radially 15 by varying the longitudinal position of the shell 8 on the mandrel 2. For example, Fig. 5 shows the parts in the position which they occupy when the blades are expanded to the maximum extent, and when in this position 20 the front end of the shell 8 is in contact with the rear face of the enlargement 3, against which it is clamped by the nut 10. In order to adjust the blades inward from this position the nut 10 is first screwed backward, the 25 shell 8 is then moved backward on the mandrel to a suitable extent, and the blades are then slid inward and forward on their slanting inner edges until the angular portion on each blade which lies beneath the corresponding projection 6 is wedged between 30 said projection and the underlying portion of the shell 8, as shown in Fig. 2, whereupon the parts are clamped by setting up the nuts 10 and 15 and the lock nut 16.

40 Fig. 2 shows the blades in an intermediate position of adjustment, their inward movement being eventually limited by the engagement of their front portions with the bottoms of the notches 4. To adjust the 45 blades outward the nuts 15 and 16 are first screwed backward on the shell 8 to a sufficient extent, the blades are then moved backward and outward until they reach the nut 15, the shell 8 is then forced forward as far 50 as possible and clamped by the nut 10, and finally the nuts 15 and 16 are again set up tightly to clamp the blades in place. In all 55 positions of adjustment the front ends of the blades are held against the shell by the projections 6, which enter the angular recesses 12 to a greater or less extent.

It will be seen that the blade-adjusting arrangement above described not only renders the use of adjusting shims unnecessary 60 but also enables the blades to be adjusted progressively, as distinguished from a step-by-step adjustment. It is to be understood, however, that within the scope of the appended claims the details of construction of

the blade-holding means and of the other parts of the tool may be modified in various ways without departing from my invention, and that my improvements are applicable to various types of reamers and similar tools.

I claim:

1. A tool of the character described, comprising a driving mandrel provided with an enlargement having blade-receiving notches therein, a shell mounted on the mandrel behind said enlargement and provided with 70 blade-receiving grooves each located in alignment with one of the notches and having its bottom slanted with respect to the axis of the mandrel, a set of blades located in said grooves and notches, means for maintaining said shell in various longitudinal positions with respect to said enlargement, and means for securing the blades in place.

2. A tool of the character described, comprising a driving mandrel provided with an enlargement having blade-receiving notches therein and rearwardly-extending projections each located behind one of the notches, a shell mounted on the mandrel behind said enlargement and provided with blade-receiving grooves each located in alignment with one of the notches and having its bottom slanted with respect to the axis of the mandrel, a set of blades located in said grooves and notches and having recesses to receive 90 said projections, means for maintaining said shell in various longitudinal positions with respect to said enlargement, and means for clamping the rear ends of the blades in place.

3. A tool of the character described, comprising a driving mandrel provided with an enlargement having blade-receiving notches therein and rearwardly-extending projections each located behind one of the notches, a shell mounted on the mandrel behind said enlargement and provided with blade-receiving grooves each located in alignment with one of the notches and having its bottom slanted with respect to the axis of the mandrel, a nut mounted on a threaded portion of the mandrel behind said shell and adapted to engage the latter, a set of blades located in said grooves and notches and having recesses to receive said projections, and a blade-clamping nut mounted on the shell and adapted to engage the rear ends of the blades.

4. A tool of the character described, comprising a driving mandrel provided with an enlargement having blade-receiving notches therein and rearwardly-extending projections each located behind one of the notches and having an inwardly and forwardly slanting rear face, a shell mounted on the mandrel behind said enlargement and provided with blade-receiving grooves each located in alignment with one of the notches

and having its bottom slanted with respect to the axis of the mandrel, a set of blades located in said grooves and notches and having angular recesses adapted to receive the 5 respective projections, a nut mounted on a threaded portion of the mandrel behind said shell, and a blade-clamping nut mounted on

a threaded portion of the shell behind said blades and adapted to engage the rear ends of the latter.

10

Signed at Boston, Mass., this eighth day of March, 1916.

GEORGE B. CHADWICK.
